UNITED STATES PATENT OFFICE

CYPREIEN VUILLAUME, OF LYON, FRANCE

BLOWPIPE

Application filed May 20, 1925, Serial No. 31,639, and in France May 20, 1924.

The present invention has for its object an oxy-acetylene blowpipe, which, however, can be used with any other gas. The improved blow pipe is characterized by means for feeding the different gases, so arranged that any back action of the flame or communication of the flame with the interior of the blowpipe are rendered impossible.

The acetylene is fed through a tube, arranged concentrically with the opening of the burner, and adjacent thereto is the oxygen feed-tube. The oxygen necessary for the combustion passes into small channels formed by striations carried by the acetylene burner. The mixing chamber is thus in the form of a cylinder having for diameter, the diameter of the orifice and for height, the length thereof. It is as reduced as possible and is practically only a few millimeters. It is therefore outside the burners that the intimate mixture of the gases is made.

A jet of oxygen, added to the whole of the preceding system, enables the blowpipe to be used for cutting purposes. Finally by capping the whole with a cap of any geometrical shape suited to the kind of work, and providing an air-feed pipe working under pressure to issue in said cap, the blowpipe can be used for cutting under water, the water being prevented from entering the cap by the air.

The annexed drawings illustrate an example of construction of the invention in which Fig. 1 is a longitudinal section through the blowpipe,

Fig. 2 is a front view of the oxygen burner, looking at the tip, and

Fig. 3 is a perspective view of same.

The blowpipe comprises an outer sleeve or tube *a* in which is fitted, at one of its ends, a spherical body *b*, which receives the supplies of gas and carries the needle-valves *c*, *d* and at the other end a metal block *b*¹ provided with different ducts and on which are screwed the burners *e*, *f*, *g*. The spherical body *b* and the block *b*¹ have their ducts connected by metal tubes *h*, *i*, *j*, *k*.

The acetylene necessary for the working of the blowpipe is fed through the tube *h*

controlled by the needle-valve *c* said tube being connected to the burner *e* ending in the form of a cone, grooved in the longitudinal direction of the burner. This burner leads into the mouth of the burner *f* which is screwed on the metal block *b*¹, at the end of the oxygen feed duct *i*, which starts in the chamber *l* which is in direct connection with the source of oxygen; the supply to the duct *i* is controlled by the needle valve *d*.

The point of burner *e* rests on the inner wall of burner *f*, and the oxygen required for the combustion escapes through the aforesaid grooves, and the acetylene is conducted to the tip by the central duct *h*'.

Connected with the chamber *l* is a second oxygen duct *j*, controlled by the valve *m* and which issues in immediate proximity to the lighted jet, to enable cutting work to be performed.

In order to be able to employ the blowpipe under water, a cap *n* of suitable shape, round, oval, etc. is screwed on the end of the apparatus and inside this cap a pipe conveying compressed air feeds, the feed being controlled by the valve *o*; this air expels the water from the cap *n* and enables the blowpipe to work.

For working under water, in the first place the compressed air valve *o* is opened, so as to expel the water from the cap *n*. Then the needle-valve *c* is opened and the gas jet is ignited by an electric device. The oxygen is fed by opening more or less the needle-valve *d*, in order to regulate the flame. The mixture being made, the valve *m* is opened to prime the cutting jet.

What I claim is my invention and desire to secure by Letters Patent of the United States is:-

A blow-pipe comprising a casing having a short end but at an angular declination, a plurality of valve controlled ducts received in said casing and extending therethrough, a conical nozzle for each duct arranged concentrically with respect to each other and mounted in the short end of the casing, the innermost of said concentrically arranged nozzles being provided with striations formed

on its outer surface, a cap secured to the free extremity of said short end about the concentrically arranged nozzle and an air duct opening rearwardly of said cap for directly delivering compressed air into the same.

5 In witness whereof I have signed this specification.

CYPRIEN VUILLAUME.
